AUTOMATIC BLOCK SIGNALING SYSTEM
FOR RAILROADS

Edwin C. Larry, Rochester, and Morton C. Twitchell, Spencerport, N. Y., assignors to General Railway Signal Company, Rochester, N. Y.

Application May 24, 1935, Serial No. 23,268

19 Claims. (Cl. 246—33)

This invention relates to automatic block signaling systems preferably of the absolute-permissive-block type, and more particularly to a primary-secondary track relay combination coordinated with other relays and devices of such a system.

In accordance with the present invention it is proposed to so interconnect a primary track relay and a secondary or repeater track relay, that the secondary relay will in accordance with the position it assumes change the pick up and drop away characteristics of the primary relay, so as to result in a more sensitive and reliable track circuit current detecting combination, and to perform other functions by this primary-secondary track relay combination. As is well understood by those skilled in this art, the signaling apparatus of an absolute-permissive-block signaling system absolutely blocks the movement of trains in an opposite direction to that of a first train in a single track section and affords permissive follow up movement of trains in the same direction through such section, and this type of system usually employs a directional stick relay for permitting such follow-up move. More specifically it is proposed in accordance with the present invention to so coordinate the primary-secondary track relay combination with the directional stick relay of the absolute-permissive-block system, that the primary track relay, which is the first to drop due to the presence of a train moving in a particular direction, will close a pick-up circuit for such stick relay and so that the stick circuit for such stick relay is controlled at least indirectly by the secondary relay.

In accordance with one form of the invention as illustrated in Fig. 2 of the drawings it is further proposed to so interconnect the primary and secondary relay of the track relay combination that the wayside signal must give a stop indication for each deenergization of the repeater or secondary track relay directly in advance of such signal, before reenergization of the secondary track relay can take place. This feature provides a check on the failure of a signal to assume the stop position, because failure of a signal to go to stop causes the secondary relay to remain down and this in turn causes the next signal in the rear to assume a caution or a stop position, even though more favorable traffic conditions exist in advance thereof.

Other objects, purposes and characteristic features of the present invention will in part be described hereinafter and will in part be obvious from the accompanying drawings, in which:—

Fig. 1 illustrates one embodiment of the present invention, in which embodiment the wayside signals are multiple aspect color light signals and therefore do not require checking of the movement of the signal to stop, since the signals have no moving parts; and

Fig. 2 shows a modified form of the invention applied to movable spectacle color light signals and including means for checking the movement of the signal spectacle to the stop position in response to traffic conditions requiring such an indication.

Figure 1

Referring to Fig. 1 of the drawings, in which only a portion of a single track section of railway track has been illustrated, the track rails 1 have been divided by insulating joints 2 into isolated sections, of which each two adjacent sections comprise a block, and of which the block N and portions of the blocks M and O only have been illustrated. Each of these isolated sections is provided with a track circuit which comprises a battery B, the track rails 1 and a track relay T in series. This track relay T comprises part of the primary-secondary track relay combination heretofore mentioned. Since these various track circuits are the same, each of the reference characters for the track batteries and track relays have been provided with a prefix corresponding to the prefix for the signal with which the track circuit is directly associated.

At the entrance to each block for each direction of traffic is provided a wayside signal, and for convenience the west bound signals have been designated 1SG and 3SG, whereas the east-bound signals have been designated 2SG and 4SG. Each of these primary track relays is interconnected with an associated secondary track relay TP, having a prefix corresponding to the prefix of the associated primary track relay. Since like parts employed in the control of each of the signals are the same the control circuits and devices of the signal 2SG will only be described, like parts for the remaining signals being assigned like reference characters having distinctive exponents or prefixes, as the case may be.

As shown in the drawings the secondary relay, or track repeater relay 2TP, is controlled by the contact 10² of the primary track relay 2T, and this relay 2TP when energized includes through the medium of its make-before-break contact 11² a greater or less portion of the winding of the track relay 2T, depending upon whether the secondary relay is in its energized or deenergized

condition. In other words, when the repeater track relay 2TP is in its retracted condition it includes the entire winding of the track relay 2T, whereas if the repeater track relay 2TP is in its attracted condition it includes in the track circuit only a portion of the winding of the track relay 2T. This expedient of changing the sensitivity of the track relay is resorted to in order to render the track relay more readily responsive to current when it is to be picked up and to render it more responsive to the shunting action of a train when it is energized and is to be de-energized by such train.

The signal 2SG is a three color aspect signal of the multiple unit color light type, which has no moving parts, a particular color unit being illuminated under a particular condition of traffic. The three color light units G, Y and R of this signal 2SG emit color beams of green, yellow and red, respectively, signifying clear, caution and stop conditions, respectively. As is readily apparent from the circuits for these signal units, the proceed lamp G is lighted when the home-distant relay 2HD is energized by current of positive polarity, the caution lamp Y is energized when this relay 2HD is energized by current of reverse polarity and the stop unit R is energized when the relay 2HD is deenergized.

Each signal has associated therewith the usual directional stick relay, which for the signal 2SG comprises the stick relay 2S. This stick relay 2S is provided with one pick-up circuit and two stick circuits. The pick-up circuit for the relay 2S includes the front contact 12² of the relay 2HD, and the back contact 13² of the relay 2T. One stick circuit for this relay 2S includes its own stick contact 14² and the back contact 13² of the relay 2T, and the other stick circuit includes the stick contact 14² and the back contact 24² of the relay 2HD.

The home-distant relay 2HD is a relay of the polar neutral-retained type, which includes a polar armature and a neutral armature, and of which the neutral armature will be retained during pole changing of the current for the relay, this neutral armature being provided with an auxiliary electro-magnet 5² inductively coupled to the main winding of the relay, so that during pole changing of the current in the main winding, a current is induced in the auxiliary electro-magnet 5² to hold the neutral armature up during such pole changing operation. For a more detailed description of a relay of this type attention is directed to the patent to Larson No. 1,852,210 dated April 5, 1932. This relay 2HD is normally energized through a circuit which may be traced as follows: beginning at the terminal B+ of a suitable source of current B located at the next signal location in advance, front contact 16² of the relay 4HD, front contact 17² of the track repeater relay 3TP, front contact 18² of the repeater track relay 2TP, winding of the relay 2HD to a common return wire C connected to the midpoint of the source B at the next signal in advance. Under caution traffic conditions this relay 2HD is energized by current of the opposite polarity through a circuit including in series the front contact 19² of the stick relay 4S, the back contact 16² of the relay 4HD, and the contacts 17² and 18² heretofore mentioned.

Operation Figure 1

In order to obtain a clear understanding of the operation of the system, it is believed only necessary to consider the movement of a train from left

to right through the blocks M, N and O. Let us assume that such a train is moving in an eastwardly direction, from left to right, in the block M. The entrance of this train into the block N will cause deenergization of the track relay 2T, which track relay 2T upon dropping will close a pick-up circuit for the relay 2S and will break the energizing circuit for the repeater track relay 2TP. This closure of the back contact 13² of the relay 2T will cause the relay 2S to be picked up. Also, dropping of the repeater track relay 2TP will cause opening of the contact 18² in the energizing circuit of the relay 2HD, thus causing de-energization of this relay 2HD. Dropping of the relay 2HD will result in dropping of its contacts 12² and 24², thereby opening the pick-up circuit heretofore traced for the relay 2S and closing the second stick circuit for this relay 2S. Dropping of relay 2HD will also cause the signal 2SG to display a danger indication by the lighting of the red lamp R. It is thus seen that the pick-up circuit for the relay 2S is directly controlled by the primary track relay 2T, whereas one of the stick circuits for this relay 2S is controlled by the repeater track relay 2TP through the medium of relay 2HD, and that a certain amount of time must elapse following the dropping of the track relay 2T, before the contact 12² of the relay 2HD may assume its retracted position to break the pick-up circuit, and that this time delay is in part provided by the intervening secondary relay 2TP. In other words, the pick-up circuit for the relay 2S is controlled by the primary portion of the primary-secondary track relay combination; whereas the stick circuit is controlled by the secondary portion of this combination. Also, this primary-secondary track relay combination 2T-2TP in itself constitutes a rather sensitive train detecting mechanism, in that the track relay 2T is so controlled by its repeater track relay 2TP that it is sensitive to train shunting when in its attracted condition and is sensitive to train un-shunting when it is in its retracted condition.

As the train in question now proceeds in an eastward direction through the block N, it will upon leaving the first track circuit of block N allow the primary-secondary relay combination 2T-2TP to assume the attracted position. This will not, however, cause deenergization of the stick relay 2S, for although one stick circuit has been broken at back contact 13² of the relay 2T, the other stick circuit including back contact 24² of relay 2HD is still closed.

Let us now assume that the train in question enters the block O. When this occurs the stick relay 4S will be picked up and stuck up in the same manner as already explained in connection with relay 2S. As the rear end of the train now leaves the block N the relays 3T-3TP pick up and with the stick relay 4S now energized current of negative polarity is applied to the relay 2HD. This will cause the yellow lamp Y of the signal 2SG to be lighted.

As the train under consideration now entirely passes out of the block O, the relay 4HD is re-energized. This causes the relay 2HD to again be energized by current of normal polarity as a result of which the signal lamp G of the signal 2SG is again lighted. As this train continues its eastward journey the signal 4SG will be returned to its normal clear condition, all in a manner as already explained in connection with signal 2SG.

Figure 2

In Fig. 2 has been shown a modified form of

the present invention, also shown applied to a single track portion including the block N and portions of the blocks M and O. In this form of the invention like parts have been designated by 5 like reference characters as corresponding parts of Fig. 1. Also, like parts for each signal location have been designated by like reference characters with exponents or prefixes corresponding to that of the signal location at which it is located. It will be noted that the track relays, repeater track relays, and directional stick relays 10 have been identified by the same reference characters as those shown in Fig. 1.

Attention is particularly directed to the fact 15 that movable spectacle light signals S¹, S², S³ and S⁴ have been shown instead of fixed aspect light signals 1SG, 2SG, 3SG and 4SG as shown in Fig. 1, and that the light signals of Fig. 2 are directly controlled by a line circuit extending 20 through the block to the next signal in advance as a result of which the home-distant relays HD are omitted from Fig. 2 of the drawings. An additional and slow acting relay GY, is also shown for each signal location in Fig. 2, this relay GY 25 being energized when the signal mechanism assumes either the proceed (G) or the caution (Y) position, and providing that the associated repeater track relay is in its energized position.

Referring to the signal S², for instance, this 30 signal includes only a single signal lamp L² which in the particular form of the invention illustrated is energized only when the opposing track repeater relay 1TP is deenergized, as illustrated by the circuit through the back contact 20² of the 35 track relay 1TP, thus affording the usual approach lighting feature.

The structure of the signal S² is such that if its winding 21² is energized by current of normal polarity the spectacle 22² is moved to its extreme right-hand position in which the green filter G intercepts the light emitted by the lamp L² so as to leave only green light in the emitted beam, suitable lens structure of course being used to produce a concentrated beam of light. Under 45 this condition the contact g assumes a right-hand position and results in energizing the clear-caution relay 2GY through a circuit including the front contact 23² of the relay 2TP. Also, if the winding 21² of the signal S² is energized by current of reverse polarity, the spectacle 22² is moved to its extreme left-hand position, in which the yellow filter Y intercepts the light from the lamp L² thus emitting a yellow beam of light. Under 50 this condition, the contact g of this signal mechanism assumes a pendent position and the contact y assumes its left-hand position, thus causing the energization of the clear-caution relay 2GY.

Under normal conditions the winding 21² of the 60 signal S² is energized through the following circuit:—beginning at the terminal (+) of a suitable source of current at the next signal in advance, front contact 27² of the relay 4GY, back contact 28² of the relay 3S, front contact 29² of the relay 3TP, front contact 30² of the relay 2TP, winding 21², and front contact 31² of the relay 4GY to the other terminal (—) of said source. If now the winding 21² of the signal S² is deenergized, as it would be by a train entering 65 the block N, the signal spectacle 22² will be turned to its middle biased position, under which condition the two contacts g and y will assume their pendent position, in which position of the mechanism the pick-up circuit for the relay 2TP, traced hereinafter, may be closed. Also, with

the mechanism of the signal S² in its middle biased position the red color filter R intercepts the light beam and causes a red signal indication to be given thus manifesting danger ahead. For a more detailed illustration and description of 5 this movable spectacle signal attention is directed to the prior application of Field Ser. No. 561,802 filed September 8, 1931. Under normal clear traffic conditions the repeater track relay 2TP is energized through a stick circuit including 10 the front contact 34² of the track relay 2T and its own stick contact 35².

Operation Figure 2

Let us assume that there is a train moving 15 from left to right in the block M under clear conditions of traffic in advance. The presence of the train in the block M will result in deenergization of the repeater track relay 1TP, resulting in closure of the back contact 20² and resulting in illumination of the lamp L², thus manifesting to the engineer that traffic conditions in advance are clear. As this train passes the signal S², its treading upon the track circuit including the track relay 2T will cause deenergization 20 of this primary track relay 2T and opening of the front contact 34², as a result of which the stick circuit for the secondary track relay 2TP is broken, thus causing the repeater track relay 2TP to also assume the retracted position. De- 25 energization of the repeater track relay 2TP will of course change the sensitivity of the track relay 2T by movement of the make-before-break contact 11² to its lower position. Also dropping of the track relay 2T will cause closure of back contact 34² of this relay, thereby closing a pick-up 30 circuit for the relay 2S, which includes the back contact 34² of relay 2T and the front contact 36² of the relay 2GY. Also, dropping of the repeater track relay 2TP will by dropping of its contact 35 30² result in deenergization of the winding 21² of the signal S², and will further result in opening of the contact 23² included in the energizing circuit for the relay 2GY. Dropping of relay 2GY will by closing its back contact 37² close a 40 stick circuit for the relay 2S, which stick circuit includes the stick contact 38² of the relay 2S. The stick relay 2S was, however, already stuck up through a stick circuit including the back contact 34² of the primary track relay 2T. It is 45 thus seen that the directional stick relay 2S is picked up by dropping of the track relay 2T and is stuck up by dropping of the relay 2GY controlled by the track repeater relay 2TP. It should be noted that the pick-up and stick circuits for 50 the directional stick relays of Fig. 2 are the same as those in Fig. 1 except that contacts of the clear-caution relay are used instead of contacts of the home-distant relay.

With the directional stick relay 2S now en- 60 ergized, and with the relay 2GY deenergized, current of negative or caution potential is applied to the signal mechanism of the next signal in the rear through a circuit starting at the terminal (+) associated with the contact g, the contact g 65 assuming its left-hand pendent position, the contact y assuming its right-hand pendent position, the front contact 40⁰ of the directional stick relay 2S, the back contact 31⁰ of the relay 2GY, to the next signal in the rear, and then back through front contact 29⁰ of relay 1TP, back contact 28⁰ of relay 1S and back contact 27⁰ of relay 2GY to the terminal (—). It will be noted that the line circuit extending from a particular signal to the next signal in advance includes front con- 75

tacts of the two track repeater relays of the block along which this line circuit extends, and that deenergization of these track repeater relays will result in opening the line circuit and in shorting it insofar as the portion of the circuit toward the signal control winding 21 is concerned. This is done in order to afford additional protection, so that the signal is not apt to be operated by foreign current accidentally applied to the line wire, as sometimes occurs by accidental crossing of line wires.

As the train in question moves from left to right through the block N the signal mechanism for the signal S² will of course remain in its middle stop position, and the lamp L² of this signal will be extinguished as soon as the rear end of the train has left the block M. Let us now assume that the train in question enters the block O. In so doing the stick relay 4S will be picked up in a manner as already explained in connection with the stick relay 2S. As the rear end of the train leaves the track circuit including the track relay 2T, this primary track relay 2T will pick up, and the picking up of this primary relay 2T will result in picking up of the repeater track relay 2TP through the following pick-up circuit:—beginning at the terminal (+) of a local source of current, contact g of the signal S² assuming its pendent position, contact y of this same signal assuming its pendent position, front contact 42² of the track relay 2T, through the winding of the secondary track relay 2TP to the other terminal (—) of said source. It should, however, be noted that this secondary track relay 2TP would not have been picked up had the signal S², for some reason or another, stuck clear and not have assumed the stop position.

It is thus seen that if a signal, such as the signal S², for instance, should be stuck in its clear or caution position even though a passing train has deenergized the repeater track relay 2TP the next signal in the rear could not receive caution energy because the circuit to such signal in the rear would be open at the contact g or y, as the case may be. Also, since the secondary track relay 2TP cannot be picked up under this condition the relay 2GY would remain deenergized and the clear circuit to the next signal in the rear cannot be closed at front contacts 27⁰ and 31⁰. In other words, the signal must follow each deenergization of its relay TP or the next signal in the rear will remain thereafter at stop. As the rear end of the train in question now passes entirely out of the block N resulting in reenergization of the repeater track relay 3TP, the signal mechanism for the signal S² will be energized by current of negative polarity through a circuit such as heretofore traced and including back contacts 27² and 31² of the clear-caution relay 4GY, the front contact 43² of the stick relay 4S and the contacts g and y of the signal S⁴. The application of this current of negative polarity to the winding 21² of the signal S² will result in operation of the signal mechanism to the caution position, where the light beam is intercepted by the yellow color filter Y, and in the event of a train moving from left to right in the block M the lamp L² of the signal S² would be lighted to produce such yellow color beam. This application of current of reverse polarity to the winding 21² of the signal S², and with the repeater track relay 2TP already energized, as heretofore assumed, the relay 2GY is again energized, as a result of which current of positive polarity is ap-

plied to the next signal in the rear of signal S² through the medium of front contacts 27⁰ and 31⁰ of this relay 2GY. Also, deenergization of the stick relay 2S results, this by reason of opening of the back contact 31² of relay 2GY, the back contact 34² already having been opened when the rear end of the train left the track circuit including the primary track circuit 2T. As the train in question now continues its movement from left to right through the block O, the signal S⁴ and all of the relays associated therewith will be returned to their normal position as already explained in connection with the signal S².

The system shown in Fig. 2 of applicants' disclosure therefore not only discloses a system of absolute-permissive-block signaling in which a directional stick relay is picked up through a back contact of a primary relay and is stuck up through a front contact controlled by a secondary relay of a primary-secondary track relay combination in which the secondary relay changes the sensitivity of the primary relay, but further provides means whereby the secondary relay of such track relay combination constitutes a stick relay which can only be picked up if the signal directly associated therewith has moved to the stop position in response to deenergization of such secondary relay. This stick feature of the secondary relay of the track relay combination causes the next signal in the rear to remain at stop in the event the associated signal sticks in a proceed position, thereby advising the engineer and the signal maintainer that a signal has accidentally stuck at clear or caution, so that the trouble may be corrected. In both forms of the invention illustrated the primary-secondary track relay combination performs the double function of constituting a sensitive current detecting means for manifesting the presence or absence of a train on the track circuit and comprises a quick dropping primary track relay which may serve to close a pick-up circuit for a directional stick relay together with a secondary track relay which may close a stick circuit for this directional stick relay which will hold such directional stick relay energized until the entire block in advance of such stick relay becomes unoccupied.

Having thus shown and described several embodiments of the present invention to show how the invention may be applied to different kinds of wayside signals it should be understood that the particular embodiments selected have not been selected to show the scope of the invention but have been selected to illustrate the nature of the invention and how it may be applied to several well known forms of signaling systems, and it should further be understood that various changes and modifications may be made to adapt the invention to other signaling systems, all without departing from the spirit or scope of the present invention except as demanded by the scope of the following claims.

What we claim as new is:—

1. In a railway signal system of the absolute-permissive-block type, the combination with a single track section of railway track, signals capable of indicating clear, caution and stop for governing traffic in one direction through said section, signals also capable of indicating clear, caution and stop for governing traffic in the opposite direction through said section, circuits for governing said signals so organized that the passage of a train through said section will cause all opposing signals to assume the stop condi- 75

- tion and to cause the signals governing traffic in the same direction to assume a stop condition as the train passes the same, a stick relay associated with each signal for when energized tending 5 to cause the next signal in the rear to assume a caution condition, a track relay associated with each signal, a repeater track relay for each track relay energized when such track relay is in its attracted condition, means for changing the effectiveness of the winding of each track relay for each unit of current flow in accordance with whether said repeater relay is in its attracted or retracted condition, a pick-up circuit for each stick relay including a back contact of its associated track relay, and a stick circuit for each stick relay including a contact controlled by its associated repeater track relay and closed when such repeater track relay is deenergized.
2. In a railway signal system of the absolute-permissive-block type, the combination with a single track section of railway track, signals capable of indicating clear, caution and stop for governing traffic in one direction through said section, signals also capable of indicating clear, caution and stop for governing traffic in the opposite direction through said section, a polar relay for each signal, a stick relay for each signal, a circuit for each polar relay extending to the next signal in advance and connected to a source of one polarity when the polar relay associated with said next signal is energized and connected to a source of the reverse polarity when the polar relay associated with said next signal is deenergized and its associated stick relay is energized, a track relay associated with each signal, a repeater track relay for each track relay picked up through a front contact of said track relay, means for changing the effectiveness of the winding of each track relay for each unit of current flow in accordance with whether said repeater relay is in its attracted or retracted condition, a pick-up circuit for each stick relay including a back contact of its associated track relay, and a stick circuit for each stick relay including a contact controlled by the associated repeater track relay and closed when such repeater track relay is in its retracted condition.
3. In an automatic block signaling system of the absolute-permissive-block type, the combination with a section of single track, of a polar electro-responsive signaling device at the entrance to each block of said section for each direction of travel through said section, a directional stick relay for each signaling device, a circuit for each signaling device extending to the next signaling device in advance and connected to a source of current of one polarity when such signaling device in advance is energized and connected to a source of current of the opposite polarity when such signaling device in advance is deenergized and its associated stick relay is energized, a track relay for each end of each block one such track relay for each signaling device, a repeater track relay for each track relay having included in its energizing circuit a front contact of said track relay, contacts on said repeater track relay for rendering said track relay more responsive to each unit of current when said repeater track relay is in its retracted condition than when in its attracted condition, a pick-up circuit for each directional stick relay including a back contact of the associated track relay, and a stick circuit for each directional stick relay including a contact closed in response to the de-

energization of its associated repeater track relay.

4. In an automatic block signaling system of the absolute-permissive-block type, the combination with a section of single track, of a polar electro-responsive signaling device at the entrance to each block of said section for each direction of travel through said section, a directional stick relay for each signaling device, a circuit for each signaling device extending to the next signaling device in advance and connected to a source of current of one polarity when such signaling device in advance is energized and connected to a source of current of the opposite polarity when such signaling device in advance is deenergized and its associated stick relay is energized, a track relay for each end of each block one associated with each signaling device, a second stick relay, a pick-up circuit for said second stick relay including a front contact of its associated track relay and a contact closed only if the associated signaling device is in its stop condition, a stick circuit for said second stick relay including a front contact of the associated track relay, contacts on said second stick track relay for rendering said track relay more responsive to the flow of current when said second stick relay is in its retracted condition than when in its attracted condition, a pick-up circuit for each directional stick relay including a back contact of the associated track relay, and a stick circuit for each directional stick relay including a contact closed in response to deenergization of the associated second stick relay.

5. In a railway signal system, the combination with a railway track divided into sections by insulating joints, a track circuit for one of said sections and including a track relay at one end and a track source of current at the other end, a movable spectacle signal adjacent said track relay capable of indicating clear and stop, a secondary track stick relay, means controlled by said secondary track stick relay for changing the responsiveness of said track relay to current in accordance with whether said secondary track stick relay is in its attracted or retracted condition, a control circuit for said signal controlled by a front contact of said secondary track stick relay, a pick-up circuit for said secondary track stick relay including a front contact of said track relay and a circuit portion closed only when said spectacle assumes the stop position, and a stick circuit for said secondary track stick relay including only its stick contact and a front contact of said track relay, whereby said secondary track stick relay cannot be reenergized if said signal did not assume the stop position in response to deenergization of said stick relay.

6. In a railway signal system, the combination with a railway track divided into sections by insulating joints, a track circuit for one of said sections and including a track relay at one end and a track source of current at the other end, a movable spectacle signal adjacent said track relay capable of indicating clear and stop, a secondary track stick relay, contacts on said secondary track stick relay which when in their attracted position include less turns of the winding of said track relay in said track circuit than when in their retracted position, a control circuit for said signal controlled by a front contact of said secondary track stick relay, a pick-up circuit for said secondary track stick relay including a front contact of said track relay and a circuit portion closed only when said spectacle

assumes the stop position, and a stick circuit for said secondary track stick relay including only its stick contact and a front contact of said track relay, whereby said secondary track stick relay cannot be reenergized if said signal did not assume the stop position in response to deenergization of said stick relay.

7. In a railway signal system, the combination with a railway track divided into sections by insulating joints, a track circuit for one of said sections and including a track relay at one end and a track source of current at the other end, a movable spectacle signal adjacent said track capable of indicating clear and stop, a secondary track stick relay, make-before-break contacts on said secondary track stick relay which when in their attracted position include less turns of the winding of said track relay in said track circuit than when in their retracted position, a control circuit for said signal controlled by a front contact of said secondary track stick relay, a pick-up circuit for said secondary track stick relay including a front contact of said track relay and a circuit portion closed only when said spectacle assumes the stop position, and a stick circuit for said secondary track stick relay including only its stick contact and a front contact of said track relay, whereby said secondary track stick relay cannot be reenergized if said signal did not assume the stop position in response to deenergization of said stick relay.

8. In a railway signal system, the combination with a wayside signal of the movable color aspect type capable of indicating proceed and stop, of a track circuit directly ahead of said signal including the usual track source of current and a primary track relay of a primary-secondary track relay combination, said primary-secondary track relay combination including a secondary relay for changing the pick-up sensitivity of said primary relay to current flow in accordance with whether said secondary relay assumes its attracted or its retracted condition, a circuit for operating said signal to the clear position including a front contact of said secondary relay, a pick-up circuit for said secondary relay including a front contact of said primary relay and contacts of said signal closed only if said signal assumes a stop position, and a stick circuit for said secondary relay including its own front contact and a front contact of said primary relay.

9. In a railway signal system, the combination with a wayside signal of the movable color aspect type capable of indicating proceed and stop, of a track circuit directly ahead of said signal including the usual track source of current and a primary track relay of a primary-secondary track relay combination, said primary-secondary track relay combination including a secondary relay for changing the sensitivity of the winding of said primary relay to the flow of current in accordance with whether said secondary relay assumes its attracted or its retracted condition, a circuit for operating said signal to the clear position including a front contact of said secondary relay, a pick-up circuit for said secondary relay including a front contact of said primary relay and contacts of said signal closed if said signal assumes a stop position, and a stick circuit for said secondary relay including its own front contact and a front contact of said primary relay, a directional stick relay for indicating the direction of movement of a train by said signal, a proceed relay, an en-

ergizing circuit for said proceed relay closed only when said signal is in a proceed condition, a pick-up circuit for said directional stick relay including a front contact of said proceed relay and a back contact of said track relay, and a stick circuit for said directional stick relay including its own front contact and a back contact of said proceed relay.

10. In combination, a railway track having two adjacent track sections, a track circuit for each track section including in series therein a primary track relay, a secondary track relay for each primary relay for changing the responsiveness of said primary relay to current flow in accordance with whether said secondary relay assumes its attracted or retracted position and controlled to repeat the position of said primary relay, a directional stick relay, a pick-up circuit for said directional stick relay including a back contact of a primary relay of one track section and a front contact controlled by the secondary relay of the next track section in advance, and a stick circuit for said stick relay controlled by said secondary relay of the next track section in advance.

11. In combination, a railway track having two adjacent track sections, a track circuit for each track section including in series therein a primary track relay, a secondary track relay for each primary relay for changing the responsiveness of said primary relay to current flow in accordance with whether said secondary relay assumes its attracted or retracted position and controlled to repeat the position of said primary relay, a directional stick relay, a pick-up circuit for said directional stick relay including a back contact of a primary relay of one track section and a contact closed only if the associated secondary relay and the secondary relay of the next track section in advance are energized, and a stick circuit closed at least as long as one of said secondary relays is deenergized.

12. In combination, a primary track relay included in a normally closed track circuit for a railway track section, a secondary track relay associated with said primary relay controlled to repeat the condition of such primary relay and in turn change the responsiveness of such primary relay to the flow of current in accordance with whether said secondary relay assumes its attracted or retracted position, a pick-up circuit for said secondary relay including a front contact of its associated primary relay and a back contact of an electro-responsive means which electro-responsive means is controlled by said secondary relay and a stick circuit for said secondary relay including a front contact of said primary relay, whereby said secondary relay cannot be picked up until said electro-responsive means has followed the previous deenergization of said secondary relay.

13. In a railway signal system, the combination with a railway track divided into sections by insulating joints, a track circuit for one of said sections and including a track relay at one end and a track source of current at the other end, a railway signal adjacent said track relay capable of indicating clear and stop, a secondary track stick relay, means controlled by said secondary track stick relay for changing the responsiveness of said track relay to current flow in accordance with whether said secondary track stick relay is in its attracted or retracted condition, a control circuit for said signal controlled by a front contact of said secondary track stick relay, a

pick-up circuit for said secondary track stick relay including a front contact of said track relay and a contact closed in response to opening of said control circuit, and a stick circuit for said 5 secondary track stick relay including only its stick contact and a front contact of said track relay, whereby said secondary track stick relay cannot be reenergized if said control circuit was not opened in response to deenergization of said 10 stick relay.

14. In combination, a track circuit, a primary track relay included in said track circuit, a secondary track relay of the stick type, a pick-up circuit for said secondary relay including a front 15 contact of said primary relay and a contact of an electro-responsive device closed only when said electro-responsive device is deenergized, a stick circuit for said secondary relay including its own stick contact and a front contact of said primary 20 relay, means controlled by said secondary relay to cause said primary relay to be more responsive to the flow of current when said secondary relay is deenergized than when energized, and a circuit for said electro-responsive device controlled said 25 secondary relay.

15. In combination, a primary track relay included in a normally closed track circuit for a railway track section, a secondary track relay associated with said primary relay controlled to 30 repeat the condition of such primary relay and in turn change the responsiveness of such primary relay to the flow of current in accordance with whether said secondary relay assumes its attracted or retracted position, a pick-up circuit for 35 said secondary relay including a front contact of its associated primary relay and a contact of an electro-responsive means controlled by said secondary relay which responsive means is energized in response to energization of said secondary 40 relay and which contact is closed when said electro-responsive means is deenergized, a stick circuit for said secondary relay including a front contact of said primary relay, and a railway signal controlled by said electro-responsive 45 means, whereby said secondary relay cannot be picked up until said electro-responsive means has followed previous deenergization of said secondary relay.

16. In combination, a primary track relay included in a normally closed track circuit of a railway track section, a secondary stick relay, an electro-responsive device controlled by said secondary stick relay, a pick-up circuit for said secondary stick relay including a front contact 55 of said primary track relay and a contact of said electro-responsive device, a stick circuit for said secondary stick relay including a front contact of said primary track relay, and means for changing the responsiveness of said primary track relay 60 to flow of current in said track circuit in accordance with whether said secondary stick relay is in an energized or deenergized condition.

17. In a railway signal system of the absolute-permissive-block type, the combination with a single track section of railway track, signals capable of indicating clear, caution and stop for governing traffic in one direction through said section, signals also capable of indicating clear, caution and stop for governing traffic in the opposite direction through said section, circuits for governing said signals so organized that the passage of a train through said section will cause all opposing signals to assume the stop condition and to cause the signals governing traffic in the same direction to assume a stop condition as the

train passes the same, a directional stick relay associated with each signal and which when energized tends to cause the next signal in the rear to indicate caution, a section of track ahead of each signal having a track circuit including a 5 primary track relay in series therein, a secondary track relay energized through a front contact of said primary track relay and which secondary relay when energized renders said primary relay less responsive to current flowing in said 10 track circuit, a pick up circuit for said directional stick relay jointly controlled by said primary and secondary track relays, and a stick circuit for said directional stick relay controlled by said primary track relay independent of said secondary 15 track relay.

18. In a railway signal system, the combination with a wayside signal of the movable color aspect type capable of indicating proceed and stop, of a track circuit directly ahead of said signal including the usual track source of current and a primary track relay of a primary-secondary track relay combination, said primary-secondary track relay combination including a secondary relay for changing the current value at which 20 said primary relay will pick up in accordance with whether said secondary relay assumes its attracted or its retracted condition, a circuit for operating said signal to the clear position including a front contact of said secondary relay, a 25 pick-up circuit for said secondary relay including a front contact of said primary relay and a circuit portion including contacts of said signal, said circuit portion being closed only if said signal assumes a stop position, and a stick circuit for 30 said secondary relay including its own front contact and a front contact of said primary relay, a directional stick relay for indicating the direction of movement of a train by said signal, a proceed 35 relay, an energizing circuit for said proceed relay 40 closed only when said signal indicates caution or proceed, a pick-up circuit for said directional stick relay including a front contact of said proceed relay and a back contact of said track relay, a stick circuit for said directional stick relay including its own front contact and a back contact of said proceed relay, and means for controlling the next signal in the rear controlled by 45 said directional stick relay.

19. In a railway signal system, the combination with a wayside signal mechanism of the movable color aspect type capable of indicating proceed and stop, of a track circuit directly ahead of said signal mechanism including the usual track source and a primary track relay of a primary-secondary track relay combination, said primary-secondary track relay combination including a secondary relay for changing the picking up 50 sensitivity of said primary relay to current flow in accordance with whether said secondary relay 55 assumes its attracted or its retracted condition, a circuit for operating said signal mechanism to the clear position including a front contact of said secondary relay, a pick up circuit for said secondary relay including a front contact of 60 said primary relay and contacts of said signal mechanism closed if said signal mechanism assumes a stop position, a stick circuit for said secondary relay including its own front contact and a front contact of said primary relay, and 65 a signal lamp for said signal mechanism controlled by the approach of a train.
